UNITED STATES PATENT OFFICE.

AUSTIN F. JACKSON, OF TAUNTON, MASSACHUSETTS.

DESIGN FOR A SPOON, &c.

SPECIFICATION forming part of Design No. 21,038, dated September 15, 1891.

Application filed July 8, 1891. Serial No. 398,841. Term of patent 14 years.

To all whom it may concern:

Be it known that I, AUSTIN F. JACKSON, residing at Taunton, in the county of Bristol and State of Massachusetts, have invented and produced a new and original Design for Spoons, Knives, &c., of which the following is a specification.

The design is intended for handles of ladles, knives, and analogous table-ware, as well as for spoons and forks, to which it is chiefly applied.

In the accompanying drawings, Figure 1 is a view of the front or obverse face of the spoon. Fig. 2 is a view of the back or reverse face of the same.

The principal features of the design for the front of the spoon-handle are the elliptical shape of the head or end *a*, the top of which has a central depression *b*, from which extends downward on the opposite edges ornamenta-

tions or arabesques *c c*, which are continued down some distance on the handle to represent a rib-like ornamentation *d*, which ornamentations *d* are also extended up to the meeting ends of the arabesques *c* and form 25 an angular depending ornament *e*. The back of the handle has the same general contour as the face, also the central depression *a* at the top, but is otherwise plain, as shown.

What I claim is—

The design for the handles of spoons, knives, &c., comprising the central depression *a* on the end of the spoon, the central ornament *b*, the side arabesques *c c*, the rib-like ornamentation *d*, and the angular depending ornament 35 *e*, as shown and described.

AUSTIN F. JACKSON.
